CLAIM

The ornamental design for a recreational boat stern, as shown and described.

DESCRIPTION

FIG. 1 is a top and rear perspective view of a recreational boat stern showing my new design, the broken lines are for illustrative purposes only and form no part of the claimed design;

FIG. 2 is a top plan view thereof;

FIG. 3 is a right side elevational view thereof, the left side elevational view being a mirror image of that shown;

FIG. 4 is a bottom plan view thereof;

FIG. 5 is a rear elevational view thereof;

FIG. 6 is a top and rear perspective view of a second embodiment of the recreational boat stern;

FIG. 7 is a top plan view of FIG. 6;

FIG. 8 is a right side elevational view of FIG. 6, the left side elevational view being a mirror image of that shown;

FIG. 9 is a bottom plan view of FIG. 6; and,

FIG. 10 is a rear elevational view of FIG. 6.
